WILLIAM DULLES, OF ENGLEWOOD, NEW JERSEY.

TANK-FLUSHING APPARATUS.

1,028,198.

Specification of Letters Patent.

Patented June 4, 1912.

Application filed December 16, 1910. Serial No. 597,680.

To all whom it may concern:

Be it known that I, WILLIAM DULLES, a citizen of the United States, and resident of Englewood, Bergen county, New Jersey, have made a certain new and useful Invention Relating to Tank-Flushing Apparatus, of which the following is a specification, taken in connection with the accompanying drawings, forming part of the same.

10 This invention relates especially to toilet tank flushing apparatus in which the flushing valve is connected with a tank which may be of glass and be free from openings adjacent its lower part so that during the 15 flushing operation the water is supplied from this tank and also simultaneously from the inlet pipe.

In the accompanying drawings, showing in a somewhat diagrammatic way several 20 illustrative embodiments of the invention, Figure 1 is an elevation of one form of apparatus, Figs. 2, 3 and 4 are enlarged sectional views of the connections and valves thereof in different position, Fig. 5 shows 25 another form of apparatus, and Figs. 6 and 7 are enlarged sectional views showing the valves thereof in different positions.

In the form of apparatus shown in Figs. 1 to 4, the tank 1 of heavy glass or other 30 suitable material may be mounted in any way at the proper height above the toilet seat 2 and this tank which is preferably free from any openings adjacent its bottom portion may have coöperating therewith the 35 siphon 6 having its shorter leg extending close to the bottom of the tank and may also have the overflow pipe 7 connected with a suitable overflow opening close to the top of the tank. The valve casing 3 of brass or 40 other suitable material has its outlet pipe 13 connected with the seat in any desired way so as to supply water thereto for flushing the same. The siphon or flushing pipe 6 is also connected with this valve casing 3 in 45 any desired way, as indicated in Fig. 1, for instance. The overflow pipe 7 may be provided with a suitable connection 8 with which is connected the lower section 9 of the overflow pipe which, as indicated in Fig. 1, 50 may be connected with the outlet pipe 13 adjacent the seat. The stand pipe 10 may, as indicated in Fig. 4, be connected with the connection 8 of the outlet pipe 7 and also with the drain passage 29 of the valve casing. The regular water supply pipe 1 may be connected with the inlet pipe or passage

5 communicating with the inlet chamber 27 of the valve casing. The inlet valve 26 of any desired form may, as indicated in Fig. 4, be located within this chamber and mounted on the valve stem 25, the upper end 60 of which may project through a suitable packing in the casing and be provided with a knob or operating portion 12 for manual operation of this inlet valve when desired. 65 The closing valve 28 may be operatively connected with this inlet valve 26 in any desired way, as by securing it on the valve stem 25 and a suitable balance valve 24 may, if desired, be provided on the lower part of 70 this stem within the chamber 31. The flushing valve 17 of any desired form may, as indicated, coöperate with a suitable seat in the lower part of the casing so as to control access between the passage 18 communicating 75 with the flushing pipe 6, and the outlet pipe 13. A suitable retarding device is preferably connected with this flushing valve and may be in the form of the retarding valve 20 mounted on the valve stem 19 which also 80 may carry the flushing valve and which may, as indicated, be guided in a suitable bearing 23 in the casing. The flushing valve may be manually operated in any desired way as through the operating lever 4 85 pivoted about the pin 14 and carrying the internal operating arm 15 of this lever which may coöperate with a suitable slot 16 in the stem 19 of the flushing valve.

When the tank has been filled, the parts 90 are in the positions indicated in Fig. 2, and it will be evident that on raising the operating lever 4 the flushing valve 17 is raised from its seat as indicated in Fig. 3 and also this serves to raise through suitable means, 95 such as the projecting portion of the valve stem 19, the coöperating inlet valve 26. Under these circumstances the water from the tank passes through the siphon and flushing pipe 6 and additional water is supplied 100 through the inlet pipe 5 to be simultaneously discharged through the outlet pipe 13 which gives the desired flushing action and at the same time minimizes the size of tank required which is further minimized 105 because it is unnecessary to use any float in this tank and thereby reduce its water capacity. With the valves in the position indicated in Fig. 3, the stand pipe 10 and drain passage 29 are emptied through the 110 drain port 21 and the weight of the valves and operating lever 4 gradually closes the

flushing valve 17 as the retarding chamber 32 is gradually filled with fluid through the restricted vent 22 above the retarding valve 20. There is, however, sufficient friction in 5 the mounting of the inlet valve 26 or its connected parts to hold this valve in open position as shown in Fig. 4, after the flushing valve is closed so that under these conditions water from the inlet pipe 5 is sup- 10 plied to fill the tank through the flushing pipe 6 as indicated. When, however, the tank has been filled to such extent that water begins to discharge through the overflow pipe 7 this water enters the stand pipe 10 15 and fills the drain passage 29 in the casing so as to enter the closing passage 30 and thus exert pressure on top of the closing valve 28. The height of the stand pipe 10 is sufficient to thus slowly close the inlet valve as the 20 water in the chamber 31 gradually escapes through a suitable constricted relief passage 59 which may, if desired, be formed in the stem 19 so that when this filling operation is completed the valves and connections are 25 in the condition indicated in Fig. 2.

In the form of apparatus shown in Figs. 5 to 7, the tank 1 of glass or other suitable material, may be similarly mounted and be provided with the siphon and flushing pipe 30 6 and with an overflow pipe 7 similarly connected adjacent the top of the tank. A suitable float 34 may be supported within the tank by having a suitable pivot or other bearing 35 mounted on the top of the tank 35 or adjacent support so as to be readily accessible and make the apparatus more reliable because free from any openings, connections or operating parts adjacent the bottom of the tank. This float through the 40 changing water level in the tank correspondingly operates the pivotally connected float stem 33 which may be used to operate the inlet valve supplying the tank and also supplying water to assist the discharge from the 45 tank during the flushing operation. In this case the supply pipe 11 and inlet pipe 5 may, as indicated, be connected with a suitable valve casing comprising the connected parts 58 to which the flushing pipe 6 and dis- 50 charge pipe 13 are connected, and 38 in which a suitable inlet valve may be mounted. As indicated, the inlet valve may be in the form of a balanced valve having two parts 40, 41, mounted on the stem 36 having 55 a suitable head 42 guided in the bracket 37 on the valve casing and pivoted to the float stem 33, as indicated. The connection or passage 43 serves to connect this casing 38 with the flushing pipe 6 and with the con- 60 nected casing 58 in which may be located a flushing valve of any suitable description such for instance as the balanced valve having its members 45, 46, mounted on the stem 47 extending through the casing and pro- 65 vided with a suitable slotted yoke 51. The

operating handle or lever 50 may be pivoted to this yoke and also pivoted to the guiding link 60 mounted on the bracket 52 on the casing. A suitable closing lever 48 of bell crank form may have its central pivot loosely mounted in the slotted yoke 51 and have one end pivotally connected to the link 49 on the float stem and its other end pivoted to the supporting link 61 pivotally mounted on the lower bracket 52.

When the tank is filled and the valves and connections in the position indicated in Fig. 5, the operating lever or handle 50 may be swung into the position shown in Fig. 6 to thereupon open the flushing valve and allow the water from the tank to descend the flushing pipe 6 and chamber 44 so as to pass the flushing valve and be discharged through the outlet pipe 13. When the water in the tank 1 has been discharged sufficiently the float 34 descends and raises the float stem 33 which opens the inlet valve, as indicated in Fig. 7, so that during the first of this action the water from the inlet pipe 5 assists in the flushing operation and then through the closing lever 48, this same movement finally closes the flushing valve so that the parts are as shown in Fig. 7. Thereupon, the water from the inlet pipe 5 flows past the inlet valve and up the flushing pipe 6 to fill the tank to such a point that the float 34 rises and thus lowers the float stem 33 and connected parts, closing the inlet valve and swinging the closing lever 48 to the outer end of the slotted yoke 51, as indicated in Fig. 5.

Having described this invention in connection with a number of illustrative embodiments, forms, proportions, arrangements and details of construction to which detailed disclosure the invention is not of course to be limited, what is claimed as new and what is desired to be secured by Letters Patent is set forth in the appended claims:

1. In tank flushing apparatus, a tank, a valve casing provided with an outlet pipe, a flushing pipe and an overflow pipe between said tank and said casing, a stand pipe communicating with a drain passage formed in said casing and connected to said overflow pipe to receive water therefrom, an inlet pipe in said casing, an inlet valve controlling the discharge from said inlet pipe, an inlet valve stem on which said inlet valve is mounted and a closing valve on said inlet valve stem and mounted in a closing chamber in said casing communicating with said drain passage to receive fluid therefrom and thereby close said inlet valve, a flushing valve in said casing controlling the discharge of water through said outlet pipe, a flushing valve stem on which said flushing valve is mounted and which is adapted to open said inlet valve, 132

- operating means to open said flushing valve and simultaneously supply water from said tank and said inlet pipe for flushing purposes, a retarding valve on said flushing valve stem and mounted within a retarding chamber in said casing, there being a drain port communicating with said drain passage to discharge fluid therefrom when said flushing valve is opened.
2. In tank flushing apparatus, a tank, a valve casing provided with an outlet pipe, a flushing pipe and an overflow pipe between said tank and said casing, a stand pipe communicating with a drain passage formed in said casing and connected to said overflow pipe to receive water therefrom, an inlet pipe in said casing, an inlet valve controlling the discharge from said inlet pipe, an inlet valve stem on which said inlet valve is mounted and a closing valve on said inlet valve stem and mounted in a closing chamber in said casing communicating with said drain passage to receive fluid therefrom and thereby close said inlet valve, a flushing valve in said casing controlling the discharge of water through said outlet pipe, a flushing valve stem on which said flushing valve is mounted and which is adapted to open said inlet valve, operating means to open said flushing valve and simultaneously supply water from said tank and said inlet pipe for flushing purposes, retarding means to retard the closing of said flushing valve and means to discharge fluid from said drain passage when said flushing valve is opened.
3. In tank flushing apparatus, a tank, a valve casing provided with an outlet pipe, a flushing pipe and an overflow pipe between said tank and said casing, a stand pipe communicating with a drain passage formed in said casing and connected to said overflow pipe to receive water therefrom, an inlet pipe in said casing, an inlet valve controlling the discharge from said inlet pipe, an inlet valve stem on which said inlet valve is mounted and a closing valve on said inlet valve stem and mounted in a closing chamber in said casing communicating with said drain passage to receive fluid therefrom and thereby close said inlet valve, a flushing valve in said casing controlling the discharge of water through said outlet pipe, a flushing valve stem on which said flushing valve is mounted and which is adapted to open said inlet valve, operating means to open said flushing valve and simultaneously supply water from said tank and said inlet pipe for flushing purposes and means to discharge fluid from said drain passage when said flushing valve is opened.
4. In tank flushing apparatus, a tank, a valve casing provided with an outlet pipe, a flushing pipe and an overflow pipe between said tank and said casing, a stand pipe connected to said tank and communicating with a drain passage provided in said casing to supply thereto water overflowing from said tank, an inlet pipe in said casing, an inlet valve controlling the discharge from said inlet pipe, a closing valve mounted in a closing chamber in said casing and communicating with said drain passage to thereby close said inlet valve, means projecting from said casing to manually operate said inlet valve, a flushing valve in said casing controlling the discharge of water through said outlet pipe, means to open said flushing valve and simultaneously supply water from said tank and said inlet pipe for flushing purposes and means to discharge fluid from said drain passage when said flushing valve is opened.
5. In tank flushing apparatus, a tank, a valve casing provided with an outlet pipe, a flushing pipe and an overflow pipe between said tank and said casing, a stand pipe connected to said tank and communicating with a drain passage provided in said casing to supply thereto water overflowing from said tank, an inlet pipe in said casing, an inlet valve controlling the discharge from said inlet pipe, a closing valve mounted in a closing chamber in said casing and communicating with said drain passage to thereby close said inlet valve, a flushing valve in said casing controlling the discharge of water through said outlet pipe, means to open said flushing valve and simultaneously supply water from said tank and said inlet pipe for flushing purposes and means to discharge fluid from said drain passage when said flushing valve is opened.
6. In tank flushing apparatus, a tank, a valve casing provided with an outlet pipe, a flushing pipe between said tank and said casing, an inlet pipe, an inlet valve controlling the discharge of water from said inlet pipe to said casing, means to automatically close said inlet valve by fluid pressure when the water in said tank has reached a predetermined height, a flushing valve and controlling means to open said flushing valve and to simultaneously supply water from said tank and said inlet pipe for flushing purposes.
7. In tank flushing apparatus, a tank, a valve casing provided with an outlet pipe, a flushing pipe between said tank and said casing, an inlet pipe to supply water to said casing, an inlet valve controlling the discharge of water from said inlet pipe to said casing, means to automatically close said inlet valve by fluid pressure when the water in said tank has reached a predetermined height, a flushing valve and operating means to open said flushing valve.
8. In tank flushing apparatus, a tank, a valve casing provided with an outlet pipe, a flushing pipe between said tank and said

casing, an inlet pipe in said casing, an inlet valve controlling the discharge from said inlet pipe, means to manually open and close said inlet valve, means to automatically close 5 said inlet valve when the water in said tank has reached a predetermined height, a flushing valve controlling the discharge of water through said outlet pipe, means to open said flushing valve and thereby simultaneously supply water from said tank and 10 said inlet pipe for flushing purposes.

9. In tank flushing apparatus, a tank, a valve casing provided with an outlet pipe, a flushing pipe between said tank and said 15 casing, an inlet pipe in said casing, an inlet valve controlling the discharge from said inlet pipe, means to automatically close said inlet valve when the water in said tank has reached a predetermined height, a flushing valve controlling the discharge of water 20 through said outlet pipe, means to open said flushing valve and thereby simultaneously supply water from said tank and said inlet pipe for flushing purposes.

25 10. In tank flushing apparatus, a tank, a valve casing provided with an outlet pipe, a flushing and overflow pipe between said tank and said casing, an inlet pipe in said casing, an inlet valve controlling the discharge from said inlet pipe, means to close 30 said inlet valve when the water rises to a predetermined height in said tank, a flushing valve controlling the discharge of water through said outlet pipe, an operating lever to open said flushing valve and means 35 to simultaneously supply water from said tank and said inlet pipe for flushing purposes.

11. In tank flushing apparatus, a tank, a 40 valve casing provided with an outlet pipe, a flushing pipe between said tank and casing, an inlet pipe in said casing, an inlet valve controlling the discharge from said inlet pipe, means to close said inlet valve 45 when the water in said tank has reached a predetermined height, a flushing valve controlling the discharge of water through said outlet pipe, means to open said flushing valve and means to simultaneously supply 50 water from said tank and said inlet pipe for flushing purposes.

12. In tank flushing apparatus, a tank free from openings adjacent its lower part, a valve casing provided with an outlet pipe, 55 a flushing pipe between said tank and casing, an inlet pipe, an inlet valve controlling the discharge from said inlet pipe into said casing, a flushing valve controlling the discharge of water through said outlet pipe 60 and operating means to open said flushing valve and to simultaneously supply water from said tank and said inlet pipe for flushing purposes.

13. In tank flushing apparatus, a tank 65 free from openings adjacent its lower part,

a valve casing provided with an outlet pipe, a siphon flushing pipe between said tank and casing, an inlet pipe, an inlet valve controlling the discharge from said inlet pipe into said casing to fill said siphon flushing pipe and thereupon fill said tank, a flushing valve controlling the discharge of water through said outlet pipe and means to open said flushing valve.

14. In tank flushing apparatus, a tank 70 free from openings adjacent its lower part, a siphon flushing pipe coöperating with said tank, a valve casing connected with said siphon flushing pipe to fill the same and thereupon fill said tank, an overflow pipe between said tank and said casing and means to stop the further supply of water to said tank through said flushing pipe when the water in said tank has reached a predetermined height.

15. In tank flushing apparatus, a tank 75 free from openings adjacent its lower part, a siphon flushing pipe extending adjacent the bottom of said tank, a valve casing connected with said siphon flushing pipe to supply water to fill said siphon flushing pipe and thereupon fill said tank and means comprising a valve through which the water flows to stop the supply of water to said tank through said siphon flushing pipe when the water in said tank has reached a predetermined height.

16. In tank flushing apparatus, a tank 80 free from openings adjacent its lower part, a valve casing provided with an outlet pipe, a siphon flushing pipe between said tank and casing, an inlet pipe, an inlet valve controlling the discharge from said inlet pipe to fill said siphon flushing pipe and thereupon fill said tank, means to close said inlet valve when the water in said tank has reached a predetermined height, a flushing valve controlling the discharge of water through said outlet pipe, means to open said flushing valve and means to simultaneously supply water from said tank and said inlet pipe for flushing purposes.

17. In tank flushing apparatus, a tank 85 free from openings adjacent its lower part, a valve casing provided with an outlet pipe, a siphon flushing pipe between said tank and casing, an inlet pipe, an inlet valve controlling the discharge from said inlet pipe to fill said siphon flushing pipe and thereupon fill said tank, means to close said inlet valve when the water in said tank has reached a predetermined height, a flushing valve controlling the discharge of water through said outlet pipe, and means to open said flushing valve.

18. In tank flushing apparatus, a tank, a valve casing provided with an outlet pipe, a flushing pipe between said tank and casing, an inlet pipe, an inlet valve controlling the discharge from said inlet pipe to fill 90

said tank, means to close said inlet valve when the water in said tank has reached a predetermined height, a flushing valve controlling the discharge of water through said outlet pipe, means to open said flushing valve and automatic means to close said flushing valve when the water has been dis- charged from said tank to a predetermined extent.
